MELON CARRIER
William R. Houston, Jr., 107 Rodgers St.,
Monongahela, Pa.
Filed Mar. 19, 1962, Ser. No. 180,467
1 Claim. (Cl. 224—45)

This invention relates generally to carrying devices and more particularly to a device for carrying garden products such as watermelons and the like.

It is commonly known that garden products such as melons, pumpkins, et cetera are awkward and difficult for a person to carry. Various devices have heretofore been used to assist a person in this task such as the device of T. Kailey disclosed in United States Patent No. 2,978,154. However, generally speaking prior devices have not been well received because of their relative complexity and cost. I have devised a melon carrier that is not only simple in its application and use but has a structural simplicity heretofore unattained that allows my carrier to be manufactured so inexpensively that they are truly disposable, i.e., they can be made cheaply enough to be given away by the produce seller and thereby avoid the necessity of the buyer carrying his own device with him, which a buyer may understandably be reluctant to do, and which likely accounts for the general lack of public acceptance of prior devices in this art.

I provide a carrier for garden produce such as watermelons and the like comprising an arched strap member formed from flexible springy material having a stiffened substantially inflexible handle portion disposed centrally thereof and stiffened substantially inflexible end portions. The ends of said end portions are forked or serrated and each turned inwardly toward the other and slightly backwardly on itself at an acute angle. The carrier thus may be formed from a single unitary strip of material. Preferably, the end portions and center portion are stiffened by corrugating said portions lengthwise. The leading edge of each end is preferably serrated to provide a number of pointed teeth therealong.

Other details, objects and advantages of the invention will become apparent as the following description of a present preferred embodiment thereof proceeds.

In the accompanying drawing I have shown a present preferred embodiment of the invention in which

FIGURE 1 is an isometric view of the invention shown in use with a melon;

FIGURE 2 is an enlarged side elevational view of the end portion of my melon carrier;

FIGURE 3 is an end elevation view taken on the line III—III of FIGURE 2; and

FIGURE 4 is a bottom plan view of FIGURE 2.

Referring now to the drawing and initially to FIGURE 1, I show my invention as it would appear in use with a melon. My melon carrier as therein shown comprises a strap member 1 which is of a generally arched configuration. Strap member 1 is made of a flexible springy material such as ordinary steel strapping or may be made of other metal or even plastic materials having the aforementioned flexible spring characteristics. Strap member 1 is corrugated such as by the furrow 2 and curled edges 3 adjacent thereto in the central portion thereof to stiffen said central portion and render it relatively inflexible so that it is suitable for a handle portion. The end portions 4 are also corrugated to provide stiff substantially inflexible sections. The respective ends 5 of said end por-

2

tions 4 are turned inwardly toward each other and moreover are turned slightly backwardly upon themselves or upwardly toward the arch of strap member 1 so as to form an acute angle A as most clearly illustrated in FIGURE 2, the reasons for which will be more fully explained hereinafter. The leading edges of ends 5 are forked or serrated to form prongs or pointed teeth 6 as best shown in FIGURE 4.

My carrier is easily applied by forcing the serrated ends 5 into the respective ends of a melon 7 and thereafter lifting the device by the handle portion to transport the melon easily and safely. The pointed teeth 6 make it a simple matter to plunge ends 5 into the melon ends and the fact that ends 5 are of strap width insures that the melon will not rotate in the carrier even though ends 5 are poorly centered in the melon ends.

The flexibility and springiness of strap member 1 permits my carrier to be used with many different sizes of melons and is thus more universal in this respect. When used with shorter melons than that shown in FIGURE 1, strap member 1 will simply flex or spring into a more pronounced arch. To insure that the carrier does not inadvertently pull out at the melon ends, I preferably provide that not only ends 5 are corrugated but also that the entire end portion 4 which extends partway up the arch is corrugated to thus prevent ends 5 from flexing out of the melon ends. To further insure against ends 5 inadvertently pulling out of the melon ends, I preferably turn each end 5 not only inwardly but slightly back on itself or upwardly toward the arch so that ends 5 dig into the melon ends even more as the carrier is lifted. Even so, it is apparent that my carrier may be easily removed from the melon by the person simply releasing the handle and pulling carrier ends 5 out of the melon ends.

It is also clear from the foregoing description that my device can be made from a single strip of material with a minimum of forming operations to provide a useful carrier article of such negligible cost that in a practical manner of speaking it may truly be termed disposable.

While I have shown and described a present preferred embodiment of the invention, it is to be distinctly understood that the invention is not limited thereto but may be otherwise variously embodied within the scope of the following claim.

I claim:

A melon carrier comprising an arched strap member of flexible springy material, said arched strap member being a continuous unitary strip of uniform width and having its end portions corrugated lengthwise whereby said end portions are substantially stiff and inflexible, the ends of said end portions each being turned inwardly directly toward the other and partly backwardly on the balance of its respective end portion to form an acute angle therewith, the leading edges of said ends being serrated to form teeth therealong, said arched strap member being corrugated lengthwise in the central portion thereof to form a substantially stiff and inflexible handle portion therein.
